UNITED STATES PATENT OFFICE.

WILLIAM J. KOLTS, OF KINGSTON, NEW YORK.

NON-REFILLABLE CONTAINER.

1,308,362.

Specification of Letters Patent.

Patented July 1, 1919.

Application filed March 19, 1918. Serial No. 223,422.

To all whom it may concern:

Be it known that I, WILLIAM J. KOLTS, a citizen of the United States, residing at Kingston, in the county of Ulster and State 5 of New York, have invented certain new and useful Improvements in Non-Refillable Containers, of which the following is a specification.

This invention has relation to non-refillable containers, and has for an object to provide a container of this nature having its inner surface corrugated, and embodying a movable bottom which is moved toward the orifice of the container as the contents 15 thereof are withdrawn, said bottom being formed in a manner to preclude its return to the bottom of the container, thereby effectively preventing the reintroduction of material.

20 A still further object of the invention is to provide a non-refillable container of the nature above set forth, which comprises few parts and those of a simple nature, insuring positive action and permitting its manufacture at a reduced cost.

In addition to the foregoing, this invention comprehends improvements in the details of construction and arrangement of parts, to be hereinafter described and particularly pointed out in the appended claim.

30 In the accompanying drawings, in which similar and corresponding parts are designated by the same characters of reference, throughout the several views in which they appear:

Figure 1 is a view in side elevation with parts broken away, to show details.

Fig. 2 is a view in edge elevation of the parts of the movable bottom in dissociated 40 relation, and

Fig. 3 is a view of the bottom in plan.

With reference to the drawings, 10 indicates a cylindrical container, open at its bottom end and tapering abruptly at its other 45 end to form a neck 11 which is threaded externally as at 12 to engage a complementary internally threaded cap 13 having a spout 14 formed therewith.

The open or bottom end is thickened as at 50 15 with a portion of its surface formed smooth and parallel to the walls of the container to form a valve seat as at 16. The thickened portion is then tapered toward the bottom to form a conical entrance for the 55 container as indicated at 17.

A movable bottom shown in Figs. 2 and 3

is then provided, the same being in the nature of a disk 18 having a boss formed integrally thereon at one side, and its periphery grooved circumferentially as at 20, the boss 60 being indicated at 19 and the groove at 19'. The groove 20 is formed right angularly, while the groove 19' is curved transversely, or concaved. A packing ring 21 of cork or other suitable material is applied to the boss 65 of the movable bottom, having its inner periphery curved transversely to fit the groove 19'. The inner surface of the container is formed with circumferential ridges or ribs 10' which are directed toward the lower end 70 or mouth of the container for a purpose which will be presently apparent.

In assembling the bottom in the container a wire ring 22 is engaged in the groove 20 of the bottom, whereby, when the bottom is inserted in the open end of the container the ring, which is split to permit its diameter to be varied, is first contracted and then expanded so as to engage the inner wall of the container and become seated between adjacent ribs 10' while still engaged within the groove 20 of the bottom, thereby preventing withdrawal of the bottom. The packing ring 21 being compressible permits itself to be forced into the constricted end of the container, the ring subsequently expanding and tightly engaging the wall of the container. In an initial position of the bottom the periphery thereof should be seated against the valve seat 16 of the thickened portion of 80 the container to form a seal to insure the retention of the contents therein. As shown in Fig. 1, the ring 22 is of such a size as to exactly lie over the union of said bottom 18 and the container, thereby insuring a liquid 85 tight connection between said bottom and container. 90

In use, the contents of the container is discharged by inverting the same whereupon, the movable bottom is pressed toward the 100 mouth by the finger and the contents forced through the spout 14.

After the container is empty, it will be obvious that the movable bottom cannot be restored to its former position since the 105 smooth under surface affords no opportunity to apply a tool thereto. Furthermore, if a tool or air pressure is introduced into the mouth of the container for the purpose of moving the bottom member, ribs 10' on the 110 inner wall of the container will absolutely prevent downward movement of the fol-

lower, owing to the secure manner in which the ring 22 is engaged against the ribs.

Having thus described my invention, what I claim as new and desire to secure by Letters Patent is:

A device of the class described, including a cylindrical container open at its bottom and tapering abruptly at its other end to form a neck, said bottom being thickened 10 with its surface formed smooth and parallel to the walls of said container to provide a valve seat said thickened portion tapering toward the bottom to form a conical entrance, the inner surface of said container being formed with circumferential sharp 15 edged ribs directed toward the lower end of said container, a removable disk shaped bot-

tom with a circumferentially grooved boss, formed on one side, said bottom having a circumferential groove, said bottom being 20 adapted to fit on said seat a compressible packing ring held in said groove, and a split wire ring held in said bottom groove arranged to engage the inner wall of said container said ring being of such a size as to lie 25 over the union of said bottom and container, whereby a liquid tight connection is formed, all arranged as and for the purpose set forth.

In testimony whereof I affix my signature in the presence of two witnesses.

WILLIAM J. KOLTS.
